US00D997946S

(12) **United States Design Patent** (10) Patent No.: **US D997,946 S**
(45) Date of Patent: ** Sep. 5, 2023

(54) **DESKTOP MULTIFUNCTIONAL DOCKING STATION**

(71) Applicant: **Shenzhen Pingemei Technology Co., Ltd.**, Shenzhen (CN)

(72) Inventor: **Shengwen Huang**, Shenzhen (CN)

(**) Term: **15 Years**

(21) Appl. No.: **35/515,018**

(22) Filed: **Aug. 9, 2022**

(80) **Hague Agreement Data**

Int. Filing Date: **Aug. 9, 2022**

Int. Reg. No.: **DM/222872**

Int. Reg. Date: **Aug. 9, 2022**

Int. Reg. Pub. Date: **Aug. 26, 2022**

CN 307645522 * 8/2022

Primary Examiner — Marie D. Fast Horse

(57) **CLAIM**

The ornamental design for a desktop multifunctional docking station, as shown and described.

DESCRIPTION

1. Desktop multifunctional docking station

1.1 : Perspective

1.2 : Perspective

1.3 : Front

1.4 : Back

1.5 : Left

1.6 : Right

1.7 : Top

1.8 : Bottom

The broken lines depict portions of the desktop multifunctional docking station that form no part of the claimed design; The shading lines indicate the character and contour of the surfaces represented, not to be confused with surface ornamentation; the desktop multifunctional docking station is used to make a convenient connection between the notebook computers and multiple accessories or external devices such as power adapters, network cables, mice, external keyboards, printers and external monitors.

1 Claim, 8 Drawing Sheets
